United States Patent Office.

FRED NORRIS, OF FREEDOM PLAINS, NEW YORK.

Letters Patent No. 99,465, dated February 1, 1870.

IMPROVEMENT IN THILL-COUPINGS.

The Schedule referred to in these Letters Patent and making part of the same.

To all whom it may concern:

Be it known that I, FRED NORRIS, of Freedom Plains, in the county of Dutchess, and in the State of New York, have invented certain new and useful Improvements in Shaft-Couplings; and do hereby declare that the following is a full, clear, and exact description thereof, reference being had to the accompanying drawings, and to the letters of reference marked thereon, making a part of this specification.

The nature of my invention consists in the construction and arrangement of a shaft-coupling, with rubber attachment, as will be hereinafter fully set forth.

In order to enable others skilled in the art to which my invention appertains, to make and use the same, I will now proceed to describe its construction and operation, referring to the annexed drawings, in which—

Figure 1 is a longitudinal vertical section, and

Figure 2 is a plan view.

A represents the axle of a vehicle, around which is placed the clip B.

This clip is provided, on its front side, with two projecting ears, C C, and between said ears the clip is grooved vertically.

The shaft-iron D, secured, in any suitable manner, to the shaft E, is forked or slotted, and fits between the ears C C.

In the slot on the shaft-iron D is inserted a piece of rubber, G, of the peculiar construction shown in fig. 1,

said rubber piece fitting in the groove on the clip B, between the ears C C.

The bolt I, which fastens, or, rather, pivots, the shaft-iron to the ears C C, passes through the rubber piece G.

By this arrangement, I obtain greater facility in removing the shafts from the wagon, the pressure of the rubber being removed when the shafts are pointed on the ground. In the ordinary mode of placing a rubber, it is very difficult to remove the bolt. The removal of the pressure, in my case, it will readily be observed, is effected by the groove in the clip. The bolt, passing through the rubber, is held thereby, and will not drop out, even if the nut should be lost, which makes it a safe coupling to use. Rattling is also entirely obviated.

Having thus fully described my invention,

What I claim as new, and desire to secure by Letters Patent, is—

The combination of the grooved clip B, ears C C, forked shaft-iron D, rubber G, and bolt I, all constructed and arranged as described, and for the purposes set forth.

In testimony that I claim the foregoing, I have hereunto set my hand, this 1st day of December, 1869.

FRED NORRIS.
